UNITED STATES PATENT OFFICE.

LULU VERHAREN LAVELL, OF MINNEAPOLIS, MINNESOTA.

DESIGN FOR A CANDLE HOLDER.

Application filed October 16, 1924. Serial No. 11,089. Term of patent 14 years.

To all whom it may concern:

Be it known that I, LULU VERHAREN LAVELL, a citizen of the United States, residing at Minneapolis, in the county of Hennepin and State of Minnesota, have invented a new, original, and ornamental Design for Candle Holders, of which the following is a specification, reference being had to the accompanying drawing, forming part thereof.

The figure is a perspective view of a candle holder, showing my new design.

I claim:

The ornamental design for a candle holder as shown.

LULU VERHAREN LAVELL.
